POOL TABLE ATTACHMENT FOR PROJECTING CUE BALLS

Willard D. Sanford, East Point, Ga. (2604 Old Hapeville
Road SW., Apt. 9, Atlanta, Ga. 30315)

Filed Apr. 12, 1971, Ser. No. 133,469

Term of patent 14 years

Int. Cl. D21—01

U.S. Cl. D34—3 R

Fig. 1

Fig. 2

Fig. 3

FIG. 1 is a top view of the pool table attachment for projecting cue balls embodying my new design;

FIG. 2 is a right side elevational view of the pool table attachment for projecting cue balls shown in FIG. 1;

FIG. 3 is a left side elevational view of the pool table attachment for projecting cue balls shown in FIG. 1;

FIG. 4 is a bottom view of the pool table attachment for projecting cue balls of FIG. 1;

FIG. 5 is a front elevational view of the pool table attachment for projecting cue balls of FIG. 1; and

FIG. 6 is a rear elevational view of the pool table attachment for projecting cue balls of FIG. 1.

I claim:

The ornamental design for a pool table attachment for projecting cue balls, substantially as shown and described.
